Application filed September 30, 1901. Serial No. 77,156. Term of patent 14 years.

To all whom it may concern:

Be it known that I, THOMAS C. JOHNSON, of New Haven, in the county of New Haven and State of Connecticut, have invented and produced a new and useful Design for a Detachable Magazine; and I do hereby declare the following, when taken in connection with the accompanying drawings and the letters of reference marked thereon, to be a full, clear, and exact description of the same, and which said drawings constitute part of this specification, and represent, in—

Figure 1, a side view, enlarged, of the detachable magazine embodying my design; Fig. 2, a vertical central section of the same.

This invention relates to a design for a detachable magazine of the so-called "box" type; and the invention consists in the configuration hereinafter described, and shown in the illustration.

The essential features of my design con-

In the sides A A' near the bottom are the narrow longitudinal grooves C, substantially parallel with each other and substantially parallel with the bottom of the magazine.

Having fully described my invention, what I claim as new, and desire to secure by Letters Patent, is—

The design for a detachable magazine as herein shown and described.
